UNITED STATES PATENT OFFICE

142,551

DESIGN FOR A TOY GUN

Leo J. Frankel, Chicago, Ill.

Application December 28, 1944, Serial No. 117,125

Term of patent 14 years

(Cl. D34—15)

To all whom it may concern:

Be it known that I, Leo J. Frankel, a citizen of the United States, residing at Chicago, in the county of Cook and State of Illinois, have invented a new, original, and ornamental Design for a Toy Gun, of which the following is a specification, reference being had to the accompanying drawing, forming part thereof.

Fig. 1 is a side elevational view of a toy gun embodying my new design;

Fig. 2 is a plan view of the gun shown in Fig. 1; and

Fig. 3 is an end elevational view looking at the handle end of the gun as shown in Figs. 1 and 2.

The dominant feature of the invention resides in a toy gun having cup-like guard plates disposed at opposite sides of the breech.

I claim:

The ornamental design for a toy gun, substantially as shown and described.

LEO J. FRANKEL.
